UNITED STATES PATENT OFFICE.

JOHN M. SWANSTROM, OF CHICAGO, ILLINOIS.

FLUID-PRESSURE REGULATOR.

1,159,431.

Specification of Letters Patent.

Patented Nov. 9, 1915.

Application filed August 2, 1913. Serial No. 782,733.

To all whom it may concern:

Be it known that I, JOHN M. SWANSTROM, a citizen of the United States, residing at Chicago, in the county of Cook, State of Illinois, have invented certain new and useful Improvements in Fluid-Pressure Regulators, of which the following is a description, reference being had to the accompanying drawings, forming a part hereof.

10 My invention relates to fluid pressure regulators by which the flow of fluid from a source of supply to a receiving tank or other receiver is lessened or increased by the increase or decrease of pressure in the receiver so as to maintain substantially constant pressure in the receiver, and my invention has for its object to provide a simple inexpensive and effective device for the purpose stated which will be adapted to be 20 set for any desired pressure in the receiver.

With these and other objects hereinafter explained in full my invention consists in the construction and combination of elements hereinafter described and particularly pointed out in the claim.

Referring to the drawings Figure 1 is a central vertical sectional view of a pressure regulator embodying my invention. Fig. 2 is a side view of the valve carrying member. Fig. 3 is a top plan view of the valve carrying member. Fig. 4 is a top plan view of the sleeve forming a part of the valve chamber. Fig. 5 is a plan view of the blank from which the screen is formed. Fig. 6 is 35 an elevation of one of the headed pins for operating the valve. Fig. 7 is a top plan view of a plate which may be used in place of the heads of the pins shown in Fig. 6. Fig. 8 is a side view of the plate shown in 40 Fig. 7. Fig. 9 is a side view of one of the headless pins used with the plate shown in Figs. 7 and 8; and, Fig. 10 is a top plan view of the valve.

In the drawings 1 is the upper, or spring chamber of the device and 2 is the lower or valve carrying member of the device. The spring chamber 1 is preferably bell shaped as shown and the lower edge of its open mouth is faced off as shown at 3. The valve carrying member has a disk 4 at its upper end having its rim raised above the main part of its upper surface and faced off as shown at 5.

6 is a diaphragm extending over the disk 4 and having its edges clamped between the rim of the disk and the edge of the spring

chamber 1, the spring chamber and valve carrying member being secured together by bolts passing through lugs 7 on the spring carrying member and corresponding lugs, 60 not shown on the spring chamber.

In the central portion of the upper face of the disk 2 is formed a recess 8 preferably crescent shaped as shown from the bottom of which a small opening 9 leads to the valve 65 chamber hereinafter described. In this central portion are also two or more holes 10 leading to the valve chamber.

On the under side of the disk 4 is a hollow extension 11 having at its upper end a head 12, having an opening 13 therein surrounded at its lower end by a valve seat 14. The head 12 is parallel with the disk 4 and between it and the under face of the disk is formed a passage 15 which communicates 75 with the opening 13 in the head 12. Communicating with this passage 15 is an enlarged inlet opening 16 screwthreaded at its outer end to receive a bushing 17 which is interiorly screwthreaded to receive the end 80 of a pipe (not shown) coming from the source of supply. The side wall of the extension 11 is so shaped as to form an abutment 18 through the upper portion of which the passage 15 extends. A screen formed 85 from a square of wire gauze 19 rests against this abutment and is held in place by the bushing 17 which bears against the corners of the square of gauze. To insert this screen it is only necessary to place the square 90 of gauze over the end of the inlet opening 16 and with any convenient blunt instrument push it into the inlet opening until it rests against the abutment 18.

20 is a sleeve screwthreaded at its upper 95 end to fit screwthreads formed on the interior of the extension 11, and having below the lower end of the extension a shoulder 21. This sleeve with the hollow extension 11 forms a valve chamber for a valve which 100 comprises a hollow body 22 open at its lower end, cylindrical on its interior and preferably hexagonal on its exterior so as to permit of the passage of the fluid between it and the walls of the valve chamber. 22 is 105 provided with a head at its upper end in the upper face of which is formed a recess to receive a disk 23 of rubber or other resilient material adapted to effect a tight closure of the opening 13. A spring 25 bearing at its 110 upper end against the inner face of the head 22 and bearing at its

lower end against shoulder 21, presses the valve toward the valve seat 14.

In the space between the upper face of disk 4 and the diaphragm 6 are the heads 5, 27 of pins 26 which extend through holes 10 into contact with the upper face of the head of the hollow body 22 of the valve. These pins are of such length that when they are in contact with the face of disk 4 they will 10 hold the valve away from the valve seat 14.

Instead of the headed pins headless pins may be used in which case a plate 28 is substituted for the heads 27, this plate being preferably provided on its lower face with 15 short pins 29 which engage the recess 8 and thus prevent it from shifting out of place.

A coiled spring 30 in the spring chamber bears at one end against a disk 31 which rests on the diaphragm 6 and at its other end 20 bears against a disk 32, which in turn bears against the end of an adjusting screw 33. The disks 31 and 32 are held against displacement by lugs 34 which engage the end coils of the spring.

25 In operation the spring 30 acting through disk 31 and diaphragm 6 on the heads 27 of the pins or the plate 28 if headless pins are used, will force them downward holding the valve away from its seat and so long as the pressure in the receiver does not exceed that desired, fluid will continue to flow from the source of supply. But if the pressure in the receiver exceeds that desired pressure in the 30 valve chamber will cause fluid to pass 35 through the opening 9 into the space between the upper face of the disk 4 and the diaphragm and will cause the diaphragm to rise, removing the pressure from the heads of the pins or the plate 28 and permitting 40 the valve to be forced against its seat by the spring 25. This action will take place automatically and as soon as the pressure in the receiver falls the valve will be again opened.

45 It will of course be understood that while for convenience of description I have referred to the spring chamber as the upper

member and the valve carrying member as the lower member the device may be reversed or may be used with the face of disk 4 at any angle desired. Preferably, however, the device will be arranged as shown.

I do not desire to be limited to the precise construction and arrangement shown as it is obvious that changes in form and particular arrangement may be made without departing from the spirit of the invention.

Having thus described my invention what I claim is:

In a pressure regulator, a valve carrying member comprising a disk having a raised 60 rim on one face and having a tubular extension concentric with the disk on its other face having a partition at its inner end parallel with the disk and having an opening therein concentric with the disk and the tubular extension, a side inlet leading to the opening in the partition, an opening leading from the interior of the tubular extension through the face of the disk, a flexible diaphragm secured at its edges on the rim of 70 the disk, a coil spring having its axis concentric with the disk and tubular extension arranged to bear against the diaphragm on the side opposite to the disk, a valve within the tubular extension adapted to fit against 75 and close the opening in the partition at the inner end of the tubular extension against the inlet pressure, a spring arranged to press the valve toward said opening, and pins extending through the partition on opposite 80 sides of the center of the central opening therein having heads above the face of the disk adapted to receive pressure from the diaphragm and having their other ends arranged to bear against the face of the valve. 85

This specification signed and witnessed this 15th day of August A. D. 1912.

JOHN M. SWANSTROM.
